UNITED STATES PATENT OFFICE.

JOHN A. PRICE, OF SCRANTON, PENNSYLVANIA.

DESIGN FOR A COOKING-STOVE.

SPECIFICATION forming part of Design No. 17,430, dated July 5, 1887.

Application filed December 4, 1886. Serial No. 290,747. Term of patent 14 years.

To all whom it may concern:

Be it known that I, JOHN A. PRICE, of Scranton, in the county of Lackawanna and State of Pennsylvania, have invented and produced a new and original Design for Cooking-Stoves, of which the following is a specification, reference being had to the accompanying drawings, forming a part thereof.

My design relates to that class of stoves wherein a heating-shelf or high closet is supported above the body of the stove proper by means of a central standard forming a smoke-flue, with or without a back supporting-plate; and the leading feature is the configuration of this central standard, as will be described.

In the drawings, Figure 1 is, a view of the design for a stove having a high closet of peculiar configuration; Fig. 2, a view of a modified form of stove having the substantially-rectangular closet, and Fig. 3 a view of a form having a shelf instead of a closet.

Heretofore the high closets have been supported by a central standard provided with a back supporting-plate, and sometimes not; but it will be seen by reference to the drawings that the leading feature is the design of the central standard, B, (A representing the stove-body proper,) with the portion C at its upper end inclined outwardly toward shelf I, and having a closet, E, thereon, as shown. This incline may extend directly from the central standard proper to the lower side of the shelf or closet, or it may terminate a short distance therefrom and be provided with a short vertical portion, D, as shown. This standard and inclined or flaring portion may be provided with any suitable ornamentation, preferably that shown, and the body of the stove may

also be suitably ornamented by designs in relief or intaglio.

The closet E may be of any suitable shape; but I prefer that shown in Fig. 1, wherein the front is rounded from the lower front portion to the point F, and from there to the back being substantially horizontal on the top. A suitable front plate, G, may be provided, if desired; but this is not essential. In Fig. 2 the closet is substantially rectangular and the back plate, H, connected with the stove top and closet is employed, and in Fig. 3 the closet is dispensed with and a shelf of any desired configuration is employed.

I claim—

1. In a design for cooking-stoves, the body A and the substantially-rectangular standard B, having the straight inclined portion C, as set forth.
2. In a design for cooking-stoves, the body A, the substantially-rectangular vertical standard B, having the straight inclined portion C at its upper end, and the vertical portion D, as set forth.
3. In a design for cooking-stoves, the body A, standard B, having the straight inclined portion at its upper end and the closet E thereon, substantially as shown.
4. The design for stoves, consisting of the stove-body, the standard B, having the incline at its upper end, and the closet I, provided with the front rounded to the point F and having a straight top and bottom, as set forth.

JOHN A. PRICE.
